RECORD READING DEVICE

Filed June 14, 1928

UNITED STATES PATENT OFFICE

JACOB T. BASSECHES, OF NEW YORK, N. Y.

RECORD READING DEVICE

Application filed June 14, 1928. Serial No. 285,313.

This invention relates to so-called phonograph records and to a method and apparatus for collecting visual impressions during the time that the record is rotated, such as for 5 playing.

It is an object of my invention to provide a method whereby a so-called phonograph record, having sound impressions thereon, may during the reproduction or while rotating 10 have made apparent or readable visually written matter printed thereon.

My invention, in its preferred embodiment, contemplates associating with a disk type of phonograph record, having a sound record 15 impressed thereon and a printed or otherwise impressed title identifying the record, of a method and apparatus for making the title or any other printed matter thereon readable during the rotation or the time that the record 20 is being played whereby the title, name or other designation relating to the record may be ascertained during reproduction without stopping the record or waiting until it has been completely reproduced.

It is a further object of my invention to provide simple and efficient apparatus whereby the name, title or other printed designation associated with a sound record may be readable and ascertainable during the time that 25 the sound record is rotating, as when the tone arm or amplifier is in the record grooves whereby during the time that a reproduction is made, the name of the title, name or other designation may be ascertained by inspection 30 from the record itself so that a permanent labelling of the record may be utilized to make the same readable during rotation or reproduction of the record.

It is a still further object of my invention 35 to provide in association with a phonograph record and the written, printed or otherwise formed visual impressions in the nature of the title, name, etc., relating to the sound record, of apparatus whereby the visually impressed 40 or printed title or name may be illuminated and become visually apparent upon a stationary object, such as a screen, whereby during the rotation or reproduction, as while playing 45 of the record, the embossed, printed or otherwise impressed designation upon the record

may be observed without interruption of the record.

Other objects of my invention reside in the provision of simple, inexpensive apparatus whereby a sound record, such as of the disk 55 type, may become readable during the rotation or playing thereof.

In the practice of my invention according to one embodiment thereof, a sound record, whether of the disk type or cylindrical type, 60 has provided thereon a plurality of repeats, printed, embossed or otherwise impressed to be visually readable, of a designation usually associated with a sound record such as the title, composer or artist, the repeats being so 65 presented in reference to some point of observation as to have the appearance of being stationary during rotation or reproduction, as while playing, of the sound record.

In the practice of my method for making 70 printed or otherwise impressed matter readable from a rotating or playing record, a plurality of repeats are presented in reference to some point of observation and then there is 75 caused at the point of observation a flickering obscuration at a speed of operation whereby the alternation will have a cumulative effect tending to give the impression of a stationary image upon the retina of the eye.

In its preferred form I associate upon a 80 sound record, such as a phonograph disk, a plurality of radial markings which pass in reference to some point of observation whereby the vision is interrupted so that the cumulative effect of a plurality of the markings will define or frame what appears to be 85 a stationary representation. It is contemplated by my method to illuminate a plurality of impressed designations in the form of radial repeats or portions of said repeats, the cumulative effect of which is to form a complete letter, syllable, word or sentence, identifying a record, and to alternately obscure 90 the same as by synchronizing the impressions in reference to points of observation with the alternations of light as may be provided from the alternating current of a house lighting system.

It is contemplated that the synchronization 95 of the alternating light and the moving re- 100

peats or portions thereof from the point of observation be such that during movement away from the specific point of observation the alternations of the current be at the dark portion thereof where as when the visual impression upon the record is completely framed or exactly at the point of observation the alternation of the current will be to effect maximum illumination. It is contemplated to provide repeats or portions thereof in such number as to be synchronized at the ordinary speed of rotation of a record, such as about 78 per minute with the customary 60 cycle, alternating current source of illumination. Perfect synchronization need not be made but that within a speed which will have the impression upon the retina to give persistence of vision as of a stationary object. Thus, the number of repeats or portions thereof may be multiplied or reduced in number. It is also contemplated that synchronization of the repeats or portions thereof as impressed upon the sound record with the alternations or the light or source of illumination may be accomplished by varying a predetermined source of constant current with the record, as by suitable contacting or make and break arrangement.

For augmenting the effect above described, it is contemplated by my invention, in the practice thereof, to position the point of observation during rotation of the record and its repeats or portions thereof so as to be substantially tangential to the rotating impressions on the record so as to be in the field of observation or framing portion at its slowest speed approaching that of being stationary relative to some point of reference. My method, therefore, includes observing or collecting visual impressions from some point approaching tangency to radial movement of the record.

To attain the objects above set forth and such further objects as may appear herein or be hereinafter pointed out and for purposes of further illustrating the method described, I make reference to the accompanying drawing forming part hereof, in which

Figure 1 is a fragmentary plan view of an embodiment of my invention as associated with a phonograph turn table;

Figure 2 is an end elevation taken in the direction of the lines 2-2 of Figure 1;

Figure 3 is a sectional elevation of another embodiment of my invention;

Figure 4 is a fragmentary plan view of a phonograph record showing another embodiment of my invention;

Figure 5 is a section taken on the line 5-5 of Figure 4; Figure 6 is a fragmentary sectional view through another embodiment.

Making reference to the drawing, in Figure 1 I have shown the top of a phonograph 10, having mounted thereon at its upper surface a turn table 11, operated by the shaft

12, upon whose central pivotal pin 13 I may mount a disk type of phonograph record 14 in the customary manner. The record 14 has associated therewith on one face, preferably at its central portion 15 a printed disk 70 having a plurality of markings 16 radially disposed. These markings may be the name, title, composer or any other designation, usually associated with a phonograph record to identify the same and to give any other information in connection with the sound record markings thereon. It is preferred to observe the markings 16 from some fixed point and for this purpose an arm 17 is provided, having one end 18 suitably orificed to move freely over the pin 13 and is preferably spaced from the record by the collar 19. Intermediate its length I provide a frame or opening 20 of a size to include one repeat of the visual impression upon the record to thus completely frame the same. It is preferred that the arm 17 be held stationary and radially disposed and for this purpose the outer end 21 is positioned behind a fixed point on the phonograph and this is preferably the tone arm 22 of the phonograph. The end 21 is so disposed as to engage the needle mounting 23 so that during rotation the loosely mounted end 18 will not be carried with the rotating carrier. It will be observed that any stationary point may be chosen from the phonograph apparatus to radially dispose the arm 17. Placed conveniently to the portion of the record having the markings, I provide a source of illumination comprising a standard 24 and a light source 25, preferably suitably shielded by the hood 26 to reflect the light upon the portion of the record having the markings. It is preferred that the source of current for this electric light be alternating current and where this is of the house current type, such as 60 cycles, the number of markings is so chosen as to be in synchronization with this type of current or, vice versa, synchronization of the light source may be effected by a commutating device operated by the record. It will be observed, also, that I prefer to put the arm 17 and its window 20 at a point whereby with a clockwise rotation of the record it may be observed at a point tangential to the record whereby the markings on the record move into the field at its slowest relative speed to the point of observation.

As previously noted, the repeats or fractions thereof are brought within the point of observation, such as the frame 20, at a time when maximum illumination is obtained from the light source 25 and moves from the frame during the dark or node of the alternation. Should synchronization be slightly off, so as to be in non-alignment with the frame 10, it will be observed that the arm 17 may be moved backwards to effect a reading.

It will be observed that by the apparatus

provided and by the means of producing step-by-step movement of the written or impressed matter on the record within a predetermined point of observation, the cumulative effect will be of a stationary object permitting reading of the impressed matter on the record. Furthermore, the stationary effect will be augmented by the point of observation being positioned at a point as near tangential to the revolving record to cause framing of or movement within the predetermined point of observation at the slowest rate of relative movement to the point of observation possible. Where it is desired to augment the effect produced by a plurality of repeats or fractions thereof and particularly to enable me, under certain conditions, to view the markings on the record from a constant or non-fluctuating source of light, I may associate with the face of the record embossed portions with the markings which it is desired to be able to read during rotation of the record upon one side of these embossed portions. For this purpose I have provided the modification shown in Figure 4 wherein a record 11a has a plurality of embossed portions 16a. These embossed portions 16a have impressed on one face thereof 16b the markings or fragments thereof which, when moving in relation to some fixed point of observation will have the cumulative effect of a stationary object. It will be observed that when viewed as in Figure 1 with the modifications thereon as shown in Figures 4 and 5 from a point substantially tangential to the rotation and at an angle to the plane of rotation substantially at right angles to the face 16b, this face will move into the field of vision at a substantially low relative speed and the tops of the embossed portions will serve to hide the face 16b when the embossed portion reaches a relative speed of movement too fast to give a stationary effect. The result will be a plurality of alternations including reflection and obscuration of light from the face 16b equivalent to that of a motion picture film and in accordance with the method previously outlined for obtaining cumulative effects of vision giving the appearance of a stationary object. It will be observed that the embossings 16a may be affixed to the plane surfaced record in the shape of a disk made from moldable composition, such as papier mâché or other moldable composition such as that of which the record is made, and which may be affixed to present types of records so as to be concentric therewith, or I may take the molding composition from which the record is made and at the time when the sound record is formed and the sound undulations or markings are embossed thereon, also form these embossed portions. For economy and particularly where a sound record is formed with sound markings on opposite faces of the disk rec-

ord, the groove between the embossings forms the high portion of the embossed portions on the opposite side of the record, as will be readily understood.

With the form shown in Figures 4 and 5 I may have a plurality of repeats throughout the entire group of radial embossings or assign a group to one letter, syllable, word or group of words and another group to another letter, syllable, word or group of words. Thus, in this form I may obtain a large amount of readable subject matter from the record during rotation thereof. This embodiment may be used with alternating current or synchronized by variation of the number of the embossed markings or by synchronization of the alternations of the lighting current to the record.

In the embodiment described in Figures 4 and 5, I am enabled, further, to project the impressions from the embossings 16b by reflection not only upon the eye of the observer but upon a fixed screen. For this purpose, in Figure 3 I have illustrated upon the phonograph 10 and the turntable 11 thereof, a phonograph record 14a, a permanent portion of the phonograph 10, such as the cover 10a having affixed to the bottom thereof a light source 25a and preferably a reflecting hood 26a. In one portion of the phonograph box, which may be in the cover member at 27, I provide in an opening 28 a translucent screen 29. This is so positioned as to be substantially parallel to the surface of the embossed portions 16b and positioned at a point best suitable for obtaining the maximum stationary effect as previously described in connection with the eye of the observer, that is, at a point substantially tangential to the rotation of the record and preferably at the forward, right hand side of a record turning clockwise and at an angle to the plane of the record so that the peak of the embossed portions will serve to alternately hide the reflecting surface as it moves at a point which will give too high a relative speed of movement to give a stationary effect. With the parts as positioned, the source of light will be projected as shown in Figure 3 by the incident beam 30 and projected forwardly by the projected beam 31 upon the rear face of the screen 29. The cumulative effect upon this screen will be that of a stationary object and may be viewed from the exterior of the phonograph cover. It will be observed that in this way during the rotation or so-called playing of the record any marking, such as the title, name of composer or artist may be thrown upon the screen 29 and be viewed during rotation of the record.

It will be understood that it is contemplated by my invention to so concentrate the light upon the face 16b and to reflect the same upon the screen 16a to obtain, if desired, magnification of the markings upon the face of

the record. It will also be observed that though I have described as the desired form of projection and reflection of visual markings from the record during its rotation from a record including the embossed portions, I 5 may obtain the same from the plane surfaced record as shown in Figures 1 and 2 by positioning the screen and the illuminating surface at the point best suited for projection, 10 reflection and observation, preferably utilizing the alternating current or the current synchronized with the plurality of repeats of markings described in connection with this embodiment.

15 Furthermore, I may, with the plane surface type of record, cause more than one reflection before projecting the material upon a screen and thus obtain the most convenient location of the screen and the light source for 20 obtaining best stationary effects.

It will further be observed that though I have described my invention in connection with a disk type of record, this is merely by way of illustration and the same may be applied to the cylindrical type of record, utilizing 25 the principle and method previously described for obtaining cumulative effects to obtain a stationary image of the markings to the eye of the observer. When used in 30 connection with the cylindrical type of record, the tangential point of observation may be obtained with greater facility.

It will also be observed that though I have described my invention and particularly the 35 markings thereof as impressed, engraved or otherwise associated as by an additional disk at the central portion of the record, I may apply these markings adjacent the peripheral portion. Furthermore, though I 40 have illustrated the repeats in Figure 1 as that of an entire word to obtain the cumulative effect simultaneously of the entire word, fractions of a letter, syllable or word or plurality of the same may be successively positioned in varying increments, the total effect 45 of which will give the desired marking on the face of the record during its rotation, as when playing.

In Figure 6 it will be observed that I have 50 illustrated a form of device wherein the improved apparent slow motion effect of the embodiments shown in Figures 3, 4 and 5 may be obtained with markings which are flat upon the record. In this view, the record 11 has its 55 central portion 15 provided with a plurality of markings 16, as described in connection with the embodiment illustrated in Figure 1. I place in overlying position upon these markings a refracting prism 20a. The refracting prism 20a may be held stationary 60 and be associated with the arm 17 at the point 20 or may be in number corresponding to the number of the markings 16. The effect of the refracting prism where the point of observation is at an angle to the plane of the

record, to bring the markings substantially transversely to the line of observation to obtain maximum slow motion as the markings pass through the zone of observation at substantially the same slow effect as obtained in the embodiments illustrated in Figures 3, 4 and 5. With either the single refracting prism as used in conjunction with the embodiment shown in Figure 1 or the multiple refracting prism as used and illustrated in Figure 6, a positioning of the markings will be obtained substantially transversely to the line of observation.

Thus, I may obtain in substantially all the forms a presentation of the plurality of markings when viewed from substantially a tangential position to the rotation an apparent position of the markings transversely to the line of observation. This presents the markings almost stationarily at one point of observation to enhance the cumulative effect of such presentation, to give persistence of vision of a stationary object.

Having thus described my invention and illustrated its use, what I claim as new and desire to secure by Letters Patent, is—

1. The method of obtaining visual readings from a moving sound record to identify the record which comprises presenting a plurality of markings associated therewith, within a zone of predetermined observation in numbers within a period of time to give persistence of vision and simulate a substantially stationary visual representation of a graphic outline.

2. The method of obtaining visual readings from a moving sound record to identify the record which comprises presenting a plurality of graphic markings associated therewith, within a predetermined zone of observation at a rate of movement the cumulative effect of which will give the appearance substantially of a stationary object.

3. The method of obtaining visual readings from a rotating sound record to identify the record which comprises presenting a plurality of identifying graphic markings associated therewith, within a zone of predetermined observation, the markings serving to have a cumulative effect to give persistence of vision and causing obscuration at intervals when said markings are out of the zone of observation.

4. The method of obtaining visual readings from a rotating sound record to identify the record which comprises presenting a plurality of graphic markings associated therewith, within a predetermined zone of observation, alternately illuminating said markings within said zone, the periods of illumination being substantially in synchronism with said markings whereby a substantially stationary reading is obtained.

5. The method of obtaining visual readings from a rotating sound record to identify

70

75

5 the record which comprises presenting a plurality of graphic markings associated therewith, within a zone of predetermined observation, the zone of observation being substantially tangential to the direction of rotation and the markings being presented transverse to the line of observation.

6. The method of obtaining visual readings from a rotating sound record to identify
10 the record which comprises presenting a plurality of graphic markings associated therewith, within a predetermined zone and concentrating a source of light upon said markings as they appear within said zone and reflecting said markings upon a screen outside
15 said zone.

7. The method of obtaining visual readings from a rotating sound record to identify the record which comprises presenting a plurality of graphic markings associated therewith, within a predetermined zone and concentrating a source of light upon said markings as they appear within said zone by alternating illumination substantially in synchronism with the appearance of the markings within said zone and reflecting the light from said markings upon a screen outside said zone.

8. The method of obtaining visual readings from a rotating sound record to identify the
30 record which comprises presenting a plurality of graphic markings associated therewith, within a predetermined zone, disposed substantially tangentially to the direction of rotation, the markings being presented substantially transversely to a source of illumination, concentrating light from said source upon said markings as they appear within said predetermined zone and reflecting the light from said markings upon a translucent screen outside said zone.

9. A sound record, having in combination therewith visual graphic markings identifying the record adapted to be readable during rotation of the sound record, said markings being disposed in number and position on said record whereby when viewed from some predetermined point of observation it will give a cumulative effect of being stationary.

10. In combination with a sound record
50 and portions thereof devoted to indication of identification of said record, markings comprising graphic outlines on said portions, said markings being so disposed and positioned as to have a cumulative visible effect when said record is moving within limits giving persistence of vision substantially that of a stationary object.

11. In combination with a sound record and portions thereof devoted to indication of
60 identification of said record, markings comprising graphic outlines on said portions, said markings being radially disposed and in number whereby they coordinate to have a cumulative visible effect when said record is moving within limits giving persistence of

vision substantially that of a stationary object.

12. In combination with a sound record and portions thereof devoted to indication of identification of said record, means for supporting markings comprising graphic outlines on said portions, said means including surfaces having reflective powers at an angle to the plane of rotation of said record whereby observation may be made angularly to
70 the record and the cumulative effect of the markings accentuated.

13. In combination with a sound record and portions thereof devoted to indication of identification of said record, angularly disposed surfaces on said portions whereby markings on said surfaces will serve to have a cumulative visible effect when said record is moving within limits giving persistence of vision substantially of a stationary outline
80 of a graphic object.

14. In combination with a sound recording device or the like adapted to include a rotating record including portions thereof devoted to indication of identification of said record and markings comprising graphic outlines disposed on said portions arranged to have a cumulative visible effect when said record is moving, means for taking observations from a predetermined portion of said record and means for illuminating said record to cause reflection within the zone of said predetermined portion.

15. In combination with a phonograph and a sound record having identifying portions including markings comprising graphic outlines so disposed and positioned as to have a cumulative visible effect within a predetermined area and means for illuminating said record disposed to reflect light from said record within said predetermined area.

16. For combination with a phonograph or the like, a sound record including portions thereof devoted to indication of identification of said record, graphic markings on said portions of said record disposed in position radially and in repeats sufficient to have a cumulative effect giving persistence of vision of a stationary object.

17. In combination with a sound record and portions thereof devoted to indication of identification of said record, of a plurality of markings including graphic outlines on said portions and means for illuminating said markings and means for directing an observer's view to said markings in a plane transverse to the line of observation and substantially tangential to the direction of rotation of said record to obtain observation of said markings at a minimum movement relatively to said line of observation.

In witness whereof I have hereunto signed my name.

JACOB T. BASSECHES.
